CONTAINER

Edgard Feder, New York, N.Y.

Application March 26, 1958, Serial No. 724,119

11 Claims. (Cl. 229—41)

This invention relates to a container, and, more particularly, is concerned with a paperboard container of the type which is utilized for enclosing an article of merchandise. More particularly, my invention pertains to a paperboard container which is made from flat stock and is cut and folded to a desired shape.

Heretofore, paperboard containers of the foregoing character have consisted of six plane sides, a typical example being a cracker box. For many years the need has been recognized for a container having a circular or otherwise curved contour, such, for instance, as a hat box which could be assembled simply by folding. However, up to the present time, it has been necessary to employ mechanical connectors, e.g. staples to manufacture a curved container.

It is an object of my invention to provide such a container, i.e. a container with curved walls which is made from a simple flat blank and is assembled to its desired final configuration merely by hand-folding operations.

It is another object of my invention to provide a container of the character described which is strong, inexpensive and easily assembled.

It is another object of my invention to provide a container of the character described which is attractive, neat and efficient.

Other objects of my invention in part will be obvious and in part will be pointed out hereinafter.

My invention accordingly consists in the features of construction, combinations of elements and arrangements of parts which will be exemplified in the container hereinafter described, and of which the scope of the invention will be indicated in the appended claims.

In the accompanying drawings in which is shown one of the various possible embodiments of my invention,

Fig. 1 is a perspective view of a closed container constructed in accordance with my invention;

Fig. 2 is a view similar to Fig. 1, but showing one plane wall of the container open;

Fig. 3 is a view similar to Fig. 2, but showing the other plane wall of the container open and both ends of the curved wall detached; and

Fig. 4 is a developed view of the curved wall.

In general, I accomplish the objects of my invention by providing a container blank including an elongated strip at least one end of which is connected to the blank near the region of attachment of the other end of the strip whereby when the blank is shaped to form a container, and both ends of the strip are located near one another, the intermediate portion of the strip, which is not connected to the blank except at its ends, assumes an arcuate shape. Moreover, the blank includes plane walls of arcuate profile which are foldable against the arcuately shaped strip and are engageable therewith both to support and rigidify the arcuately curved strip and to close the container of which the arcuately curved strip constitutes a curved wall.

Referring now in detail to the drawings, the reference numeral 10 denotes a container constructed in accord-

2

ance with my invention. By way of example, the container illustrated is for enclosing small articles, such as vials of perfume, that are to be sold across the counter. Except for a handle hereinafter described, the container entirely constitutes paper, the same being in the form of light, comparatively flexible paperboard, that is to say, paperboard which is strong enough to retain its own shape, and yet is flexible enough to be bent.

In the form of my invention being described, the container is made of two pieces of paperboard. However, as will be appreciated from the description which follows, if desired the container can be made from a single piece of paperboard. In essence the container comprises a paperboard blank 12 in the approximate shape of a strip, and a second paperboard blank 14 in the approximate shape of a flat dumbbell.

The blank 12 consists of an elongated body of generally straight configuration which when initially blanked out, i.e. when flat, has the shape best shown in Fig. 4. Said strip includes two ends, 16, 18 and two longitudinal edges. Integrally protruding at spaced intervals from each longitudinal edge is a series of rounded spaced tabs 20. Each tab on one edge may, as shown, be transversely registered with a tab on the other edge, that is to say, the tabs may be arranged in transverse pairs. However, this is not essential to the operation of my invention. Desirably, although not necessarily, the spaces between the tabs on the longitudinal edges are equal to the breadths of the bases of the tabs. The strip is provided with a transverse slit 22 near each end edge thereof, the slits adjacent the opposite ends opening at different longitudinal edges. The length of each slit is equal to at least about one-half the width of the strip. At the base of each tab 20, the strip is provided with a straight fold line 24 which connects the opposite ends of the sides of the tab so that the fold line is a continuation of the break formed by the tab in the longitudinal edge from which the tab extends, thereby at each longitudinal edge, the folds 24 and the portions of the edge between the tabs constitute a straight line.

The dumbbell shaped blank 14 includes two substantially circular panels 26, 28, joined by a short strip 30. The junctions between the side edges of the strip 30 and the panels 26, 28 constitute parallel straight fold lines 32. The width of the strip 30 is equal to the width of the strip 12. Extending integrally from the ends of the strip 30 are flaps 34 which are joined to said ends by parallel straight fold lines 36. A slit 38 is formed at the juncture between each flap 34 and the strip 30 for a distance equal substantially to at least one-half of the width of said strip. The two slits 38 extend inwardly from opposite longitudinal edges of the strip 30.

Each circular panel 26, 28 is provided with a series of spaced rounded tabs 40 arranged around its periphery. The spacing between the tabs in these series is substantially equal to the widths of the tabs 40 at their bases, and moreover the spacing between the tabs 40 is substantially equal to the widths of the tabs 20, while the spacing between the tabs 20 is substantially equal to the widths of the tabs 40. Each tab 40 is joined to its associated circular panel by a straight fold line 42 which extends between the ends of the sides of the tab. It will be appreciated that the panels 26, 28 are not circular in a strict sense, inasmuch as their peripheries include the straight folds 32 and the straight folds 42. Nevertheless, the folds 42 are very short and do not noticeably affect the circular outline of the panels. Likewise, the folds 32, although longer than the folds 42, still are short compared to the peripheries of the panels so that they too do not greatly detract from the generally circular outlines of the panels. Moreover, it will be understood that I simply have picked the circular outline as illus-

trative, and it is within the scope of my invention to utilize any curved outline for the panels 26, 28, as for instance, an oval shape.

One of the tabs 40 on each of the circular panels, and preferably the tab which is diametrically spaced from the fold line 32, includes a slot 44 which extends inwardly from a side of the tab and slants away from the fold 32. The tabs on the two panels having the slots 44 are in registered positions. However, the slots extend inwardly from opposite sides of the tab. The bases of the two slots are in registry when both of said slotted tabs are infolded to overlie what will be described hereinafter as the circular side wall of the container.

The lengths of the sundry tabs 20 and 40 are not critical. However, it is necessary that these lengths be no greater than the width of the strip 12.

To assemble the container 10 so as to prepare it for reception of merchandise, one end of the strip 12 is placed adjacent one end of the strip 30 with the slits 22 and 38 facing one another. Then the two strips are secured to one another by interengaging the slits to their full depths. In other words, a portion of the strip 12 adjacent an end thereof is slipped into one of the slits 38, and at the same time the portion of the strip 30, including one of the panels 34 is slipped into one of the slits 22 so that the two strips nest with one another. The other end of the strip 12 is similarly engaged with the other end of the strip 30. The result will be a bowing of the strip 12 between the two ends of the strip 30. It should be mentioned at this point that pursuant to my invention, the length of the strip 12 intermediate the two slits 22, is greater than the length of the strip 30 between the two slits 38 and preferably, although this will depend upon the desired design of the container, the length of the strip 12 between the slits 22 is considerably greater than the length of the strip 30 between the slits 38. In a typical embodiment of my invention, such as the one shown herein, these lengths are in approximate ratio of 6 to 1.

The shape which will be assumed by the strip 12, if otherwise unstressed, is approximately circular, save, of course, for the gap between the slits 22. However, the strip 12 is flexible, and therefore as soon will be pointed out, can be made to assume a shape other than circular, providing the departure is not too great. Nevertheless, in the preferred form of my invention, the strip 12 will, at the time of its connection with the strip 30 naturally assume some attractive curved configuration, and this is the configuration which I prefer said strip to maintain in the final form of the container.

It should be observed that the flaps 34 and ends of the strip 12 are so arranged as to be within the closed contour defined by the strips 12, 30.

The tabs 20 and 40, and the spaces therebetween on the strip 12 and circular panels 26, 28 are so positioned that when the strip 12 is connected in the foregoing manner with the strip 30, and when, thereafter, the circular panels 26, 28 are folded toward the strip 12 so as to lie in the planes defined by the longitudinal edges of the strip, the tabs on the circular panels will be registered with the spaces between the tabs on the strip. The widths of the tabs are all equal and a snug fit in the spaces between the tabs. Thus, when the tabs 40 are folded toward the strip 12 out of the planes of the circular panels 26, 28, and said panels subsequently are swung toward and against the longitudinal edges of the curved strip 12, the tabs 40 will enter into the spaces between the infolded tabs 20, and frictionally engage the side edges of the tabs 20 so as to hold the circular panels 26, 28 closed against the curved strip 12, thereby forming a container. Infolding of the circular panels is limited by the folded in tabs 20 against which the circular panels abut as they arrive at their correct position. Moreover, the tabs 20 interlock with the side edges of the tabs 40, whereby further to

strengthen the connection between the circular panels and the curved strip 12. It will be appreciated that this interengagement between the tabs 20 and 40 will cause the curved strip 12, which is flexible, to follow the contours of the peripheries of the circular panels 26, 28, both of which are identical. However, it is not desired to have the shape of the panels 26, 28 substantially different from the shape assumed by the strip 12 when unengaged by the panels 26, 28, inasmuch as this creates additional labor in assembling the container.

Due to the fact that the tabs 20 are relatively narrow, that is to say, narrow with respect to the total lengths of the peripheries of said panels, said tabs and the fold lines 42 connecting them with the panels do not, as has been noted above, noticeably affect the deviation from circularity so that the finished container is not appreciably different in general configuration from a hat box or similar container.

It will be understood by those skilled in the paperboard art that it is within the scope of my invention to make both the strip 12 and the blank 14 of a single piece of paperboard, either by having one end of the strip 12 integral with the strip 30, leaving the other end free for subsequent connection to the other end of the strip 12, or by having the strip 12 divided, e.g. in half, with one end of each half integrally connected to a different end of the strip 30 and the other end of each half detachably joined to one another as by the use of paper locks such as have been described above. However, it is desired to point out that I do not prefer the use of such a single blank inasmuch as it causes too great a waste of stock.

After the two circular panels have been folded to lie against the opposite longitudinal edges of the now curved strip 12 so that the two panels are parallel to one another, the said panels being held in this position by frictional interengagement between the tabs 20, 40, I manipulate the tabs 40 which have the slots 44, these tabs not having been infolded to lie against the inner surface of the strip 12. I infold these two tabs against the outer surface of said strip 12, first folding the tab on one panel, and then that on the other. During the infolding of said tabs, and as they are caused to lie flat against the outer surface of the strip 12 and one another, I introduce into the slots 44 a loop 46 fashioned from an elongated piece of limp material, e.g. a string, which is secured to the strip 12 and extends outwardly therefrom. When the slotted tabs 40 are folded down against the strip, one on top of the other, only short sections of the two slots 44 will be in alignment, and the loop will extend through said sections, thereby holding the slotted tabs in place. In addition to holding the slotted tabs locked, the loop can be utilized as a handle to aid in carrying the container.

It will be appreciated the number of tabs 20, 40 on the strip 12 and circular panels can vary as desired, the greater the number, the less the deviation from a curved shape being noticeable. In actual practice I have found that tabs covering an arc of as much as 30° will provide a completely satisfactory finished appearance in the container.

It thus will be seen that I have provided a container which achieves the various objects of my invention, and is well adapted to meet the conditions of practical use. As various possible embodiments might be made of my invention and as various changes might be made in the embodiment above set forth, it is to be understood that all matter herein described or shown in the accompanying drawings is to be interpreted as illustrative and not in a limiting sense.

Having thus described my invention, I claim as new, and desire to secure by Letters Patent:

1. A container comprising an elongated strip of flexible sheet material, two panels of the same material in one piece with and integrally connected to opposite transversely registered portions of the longitudinal edges of

the strip by parallel fold lines coincident with said longitudinal edges, the longitudinal axis of said strip being curved so that the strip forms a short open-ended tube of which the strip constitutes the side wall, said panels being so contoured as to constitute closures for the open ends of said shape, said strip being provided at opposite longitudinal edges thereof along its length exclusive of said fold lines with spaced tabs, and said panels being provided along their peripheries except at the fold lines with spaced tabs which intermesh with the spaced tabs of the strip.

2. A container as set forth in claim 1 wherein the strip includes at least a first portion and a second portion, the first portion being in one piece with the two panels, and the second portion having its ends interengaging the ends of the first portion.

3. A container as set forth in claim 1, wherein the spaced tabs along the strip have the edges thereof frictionally engaging the spaced tabs along the panels.

4. A container as set forth in claim 1 wherein the strip and the longitudinal edges thereof are straight, and wherein the panel tabs are joined to the panels by fold lines.

5. A container as set forth in claim 1 wherein the strip includes at least six tabs on each longitudinal edge 25 thereof.

6. A container as set forth in claim 1 wherein the length of the strip, exclusive of the fold lines, is substantially greater than the length of the fold lines.

7. A container as set forth in claim 1 wherein the length of the strip, exclusive of the fold lines, is at least five times the length of the fold lines.

8. A container as set forth in claim 1 wherein the tabs on the panels are in registry.

9. A container as set forth in claim 8 wherein two registered panel tabs, one on each panel, include non-registered slots extending inwardly from different edges of the tabs and having overlapping portions, and wherein the strip is provided with an elongated limp member extending through said overlapping portions of the slots to lock the registered tabs together.

10. A container as set forth in claim 1 wherein the tube is of substantially circular contour, except at the fold lines, and wherein the contours of the panels are of substantially the same contour except at the fold lines.

11. A container as set forth in claim 2, wherein the first portion has slots extending inwardly from its longitudinal edges adjacent each end thereof, wherein the second section has similar slots, and wherein the sections are engaged by meshing of the slots.
